UNITED STATES PATENT OFFICE.

JOHN FISH, OF SUMMIT, NEW JERSEY.

BACK-ACTING STEAM-ENGINE.

SPECIFICATION forming part of Letters Patent No. 242,908, dated June 14, 1881.

Application filed January 15, 1881. (No model.)

To all whom it may concern:

Be it known that I, JOHN FISH, of Summit, in the county of Union and State of New Jersey, have invented a new and useful Improvement 5 in Steam-Engines, of which the following is a specification.

My invention relates to improvements in that class of engines where the motion is transmitted from the piston-rod cross-head near one 10 end of the cylinder to the crank-shaft placed near the other end of the cylinder.

The object of my improvements are, first, to form the crank in such a manner that the distance between the crank cheeks or throws is 15 such as to allow the piston with its rod to pass between the cheeks or throws of the crank when it is necessary to withdraw it from the cylinder; second, the arrangement and construction of a connecting-rod formed of side 20 bars attached to a single pin at one end for the cross-head, and to a single crank-pin box extending the whole length of the crank-pin at the other end, whose cheeks or throws are wide enough apart to allow the piston to pass 25 through them.

The advantages I obtain by this construction and plan of engine and arrangement of parts are these: Where two or more cylinders and their piston-rods are connected in line, and 30 the motion given to the crank is taken from a cross-head between them, or from the cross-head where there is only one cylinder, access to the piston cannot be had without disturbing the intermediate parts, unless the cylinders are bolted onto an independent frame or bed-plate at the cross-head end of the cylinder. In my plan there is no bed-plate or frame required, and if access to the piston is sought at the other end of the cylinder, as they 35 are now constructed, the crank-shaft obstructs the way, so that it has to be removed before the piston can be examined or removed from the cylinder.

It has been the usual practice in back-acting engines to transmit the motion from the cross-head to the crank-shaft by means of two side rods to two crank or disk wheels, each wheel having its own crank-pin. A fatal objection to this practice, more especially where high 40 speed is required, is that the rods cannot be kept at the same length, as the journal-boxes

wear, and the slack is taken up. Consequently a side strain is thrown upon the cross-head, and the friction and strain upon the engine are dangerously increased. Forked connecting- 55 rods have also been used to transmit motion from a cross-head of a back-acting engine, but always with a box upon the crank-pin so short as to prevent the piston from being removed from the cylinder without disturbing the shaft, 60 and the cross-head ends of the rod had each separate boxes, producing the same evils that exist with two separate rods.

It will be observed, by referring to the drawings attached to this specification, that although I use two side rods spanning the cylinder, they virtually act as one rod in transmitting the power, for at one end they are connected rigidly to one pin, which has its bearing in the cross-head, and at the crank end they are connected rigidly to one box, this box being the full length of the crank-pin, so that when any lost motion by wear is taken up it is taken up the whole length of the bearing.

It will be noticed that the distance from the 75 center of the shaft to the crank end of the cylinder is such as to allow the crank-pin and its box just room enough to properly clear. By this means the shaft pillow-blocks can be made very stiff and rigidly attached to the cylinder. 80 At the same time a connecting-rod is obtained of a length of eight times the crank.

In this engine a bed-plate or frame is entirely dispensed with. Where an air compressor or pump is driven directly by the piston-rod of 85 this engine the crank and shaft may be placed at the end of either cylinder, as required. I attain these objects by the mechanism illustrated in the accompanying drawings, in which—

Figure 1 represents a side elevation of the engine. Fig. 2 is a section taken through the pillow-block in the line *a a*, also showing crank-shaft. Fig. 3 is a plan of Fig. 1, showing a section through cylinder and pillow-block.

A is the steam-cylinder; B, cross-head guide and distance-piece connecting steam-cylinder A and air or water cylinder C. D is a cross-head pin attached rigidly to side bars I I of connecting-rod. E is a single crank-pin box, 100 with its cap attached to crank-pin end of connecting-rod; F F, cheeks or throws of crank,

made wide enough to allow piston G to pass between them when it is necessary to remove it from the cylinder or to examine it. J is the crank-pin. H is the eccentric-rod.

5 Similar letters refer to similar parts in the different views.

What I claim as my invention, and desire to secure by Letters Patent, is—

1. In a back-acting engine having only a single crank-pin attached to two throws or cheeks, which are a sufficient distance apart to permit the piston and its rod to pass between them when it is necessary to remove them from the cylinder, a connecting-rod formed 15 of two bars, attached rigidly at one end to a single journal-pin for the cross-head and at

the opposite end to a single crank-pin box, constructed substantially as described, and for the purpose as herein set forth.

2. The combination of a connecting-rod 20 formed of two bars, which are rigidly attached to a single cross-head pin at one end and to a single crank-pin box at the other end, with a crank so arranged as to permit the piston and its rod to pass between the crank-cheeks 25 when it is necessary to remove it from the cylinder, constructed and arranged substantially as and for the purpose herein set forth.

JOHN FISH.
